FUEL INJECTION PUMP

Ernest C. Gambrell, Wichita Falls, Tex.

Application February 13, 1943, Serial No. 475,821

9 Claims. (Cl. 103—37)

This invention relates to an improvement in fuel injection pumps designed primarily for supplying liquid fuel in metered quantities and at timed intervals to an engine, such as a Diesel engine, the pump being designed for supplying fuel to the cylinders of a multiple cylinder engine or the like.

Many different types and constructions of fuel injection pumps have been proposed heretofore, but most of these have been impractical because of lack of or insufficient adjustment to accommodate them to the various conditions of operation of the engine supplied thereby, or they have been so complex that the construction and use thereof would be impractical.

The object of this invention is to simplify and improve the construction of a pump of this character not only to reduce the number of structural parts thereof for practical use, but also to provide therein in a simple and effective manner for the ready adjustment of the quantity of fuel or liquid to be discharged thereby. At the same time, where the pump is so connected as to supply liquid to a plurality of cylinders, provision is made in this invention for uniformly and simultaneously adjusting the quantity of liquid discharged by each of the pump plungers so they will supply uniform measured quantities even when adjusted to different amounts.

In the preferred embodiment of the invention, the pump is constructed of a housing that is adapted to be mounted stationary with the engine that is to be supplied thereby having cylinders uniformly spaced from each other, as around a common axis, which cylinders have fuel inlet ports and fuel outlet or discharge openings, and have plungers operating in said cylinders, which in their working stroke, draw fluid into the cylinder and discharge fluid from the cylinder. Provision is made for operating the pump plungers in timed relation with the engine and with each other, as by means of a cam.

An important feature of this invention is in the assembly and relation of these parts, together with means for adjusting bodily the pump plungers and their operating means, relative to the housing and pump cylinders. Such adjustment is accomplished in the preferred embodiment of the invention by raising and lowering the rotary cam plate to adjust the plungers in the pump cylinders and thereby vary the positions of the plungers with respect to the fuel inlet ports, thereby varying the charges of fuel drawn into the respective cylinders and the proportionate part thereof discharged through the respective outlet ports

upon operation of the plungers. By thus adjusting the plunger operating means bodily, all of the pump plungers are adjusted simultaneously and to the same extent thereby maintaining the timed relation therebetween and providing for uniform charges to be discharged from the respective cylinders.

I have shown a preferred embodiment of the invention in the accompanying drawings, in which:

Fig. 1 is a side elevation of a pump made in accordance with this invention;

Fig. 2 is an enlarged vertical section therethrough, partly in elevation;

Fig. 3 is a horizontal sectional view therethrough on the line 3—3 of Fig. 2;

Fig. 4 is a similar view on the line 4—4 of Fig. 2;

Fig. 5 is a similar view on the line 5—5 of Fig. 2; and

Fig. 6 is a side elevation of the cam plate detached.

The pump is constructed of a housing designated generally by the numeral 1, preferably formed of two parts, 2 and 3, each of which is substantially cup-shaped, and which parts are arranged in vertical alignment with each other with their meeting edges abutting, and detachably connected, as by means of a clamping ring 4, having screw-threaded connection with the part 3, and bearing upon a shoulder on the part 2. The detachable connection of the upper and lower parts 2 and 3 of the housing is located adjacent the middle of the housing to facilitate the construction and assembly of the parts. The lower end of the housing 1 has a flanged seat 5 formed thereon for mounting the pump on an engine or other stationary support.

The upper housing member 2 is constructed with a fuel intake chamber 6 in the upper end portion thereof, which chamber has an inlet pipe 7 connected therewith to admit liquid into the intake chamber, as will be evident from Fig. 3.

The closed end of the upper housing member 2 has a plurality of pump cylinders 8 mounted therein and projecting through the intake chamber 6. The cylinders 8 are spaced on different sides of the axis of the pump, and while any desired number of cylinders may be used, according to the number of cylinders of the engine to be supplied thereby, two of these cylinders are shown in the pump illustrated. Each of the cylinders 8 is rigidly mounted in the end wall structure of the housing member 2, clamping said end

wall structure between a flange 9 on the cylinder and a nut 10 threaded thereon, as shown in Fig. 2.

Each cylinder 8 has an internal pump chamber 11 therein which has intake ports 12 in open communication with the intake chamber 6, so as to admit liquid from said intake chamber into the pump chamber 11 when the ports 12 are uncovered. The upper end of the pump chamber 11 has a discharge opening, shown as provided with a threaded outlet connection 13 and a check-valve 13a therein to permit discharge therethrough of the liquid from the pump, and said check-valve prevents the drawing in of the liquid upon the back stroke of the pump.

A plunger 14 is mounted in the pump chamber 11 of each cylinder to reciprocate therein. The outer end of the plunger 14 has a cap plate 15 connected therewith against which bears a coiled spring 16, as shown in Fig. 2. The spring 16 is interposed between the cap plate 15 and a seat in a shelf plate 17 mounted within the housing 1. The shelf plate 17 is shown as a flange on a sleeve 18 which extends into a recess in a tappet guide block 19. The shelf plate 17 and the sleeve 18 are secured to the block 19 by a stud bolt 20, which extends through the sleeve and is screw-threaded into the block. The bolt 20 may be inserted through a thimble 21 in the closed end of the top housing member 2, which opening is normally closed by a snap-on cap 22. This opening through the thimble serves also as a breather for the pump mechanism, as well as an opening for lubricating the internal parts of the pump.

The head at the outer end of each pump plunger 14 bears upon a tappet 23, slidably mounted in an orifice 24 in the guide block 19, which tappet 23 has a roller 25 in position to bear upon the upper face of a cam plate 27 and to bear upon the cam 26 which is formed on the upper face of the cam plate 27 when the rotary movement of the cam plate in the operation of the pump brings the cam 26 under the roller.

The cam plate 27 has a depending sleeve 28 therefrom, and is rotatably mounted upon anti-friction bearings 29 within a carriage block 30. The cam plate 27 has a hub member secured to the upper side thereof with a reduced portion 42 journaled in a bearing 38 in the carriage block 19. The block 30 has its upper edge surrounding the cam plate 27, and has the tappet guide block 19 seated thereon. The blocks 19 and 30 are mounted in the housing 1 for vertical adjustment relative thereto, but are held against turning movement therein by keys 31 (Fig. 5) in opposite sides of the housing, in the form shown.

To provide for such vertical adjustment, I have shown a cam structure to move the carriage assembly relative to the housing, which cam structure may be formed, according to this embodiment of the invention, by means of a coarse internal thread 32, within the lower end portion of the block 30, and which thread 32 receives a coarse cam thread 33 of a rotary member 34. The rotary member 34 is provided with a toothed peripheral portion 35, meshing with teeth on a rack member 36 adapted to be adjusted lengthwise transversely through the housing to rotate the member 34 and adjust thereby the vertical positions of the blocks 19 and 30 in and relative to the housing 1.

The rotary member 34 has a peripheral flange 43 seated in the lower portion of the housing part 3, and is journaled on a sleeve 44, and in which sleeve is journaled a drive shaft 37. The sleeve is rigidly mounted in the bottom end wall

structure of the pump housing with said end wall clamped between a shoulder 45 on the sleeve and a nut 46 thereon.

The pump drive shaft 37 extends axially into the lower end of the housing 1 and journaled in the sleeve 44. The drive shaft 37 has a splined connection 39 with the cam plate sleeve 18, which splined connection 39 is nevertheless slightly spiral to cause slight circumferential adjustment of the cam plate 27 when the carriage assembly is adjusted vertically relative to the housing and the shaft 37. The enlarged top end 39, that is splined abuts against the upper end of the sleeve 44, and a drive pinion that would be secured to the lower end of the shaft for connecting the pump with the driving means, would abut against the lower end of the sleeve 44, whereby the drive shaft would be rotatably mounted in the sleeve 44 but would be held against axial movement therein.

Also, this sleeve 44 rigidly mounted in the bottom of the housing, serves as a spindle rotatably mounting the rotary member 34 thereon, said rotary member being held against axial movement by reason of abutting against a shoulder 47 at the upper end of the sleeve, and having the flange 43 seated in the end wall structure of the housing, as described above. The hub portion of the rotary member 34 projects downward, having the gear teeth 35 which engage the teeth of the transverse adjusting rack 36, whereby transverse adjustment of the rack 36 rotates the rotary member 34 about the axis of said rotary member, which is likewise the axis of the sleeve 40 and the shaft 37.

It will be evident from this structure that the blocks 19 and 30 and their connected parts constitute an adjustable carriage assembly that may be moved vertically within and relative to the housing, including the actuating cam and the pump plungers as well as the springs acting thereon. The blocks 19 and 30 may be secured together as by bolts or screws 40 (Fig. 5). With the plunger spring shelf plate 17 also secured to the block 19, it is evident that these parts will be adjusted in either direction by an adjustment of the block 30, while being held against turning movement relative to the housing by the keys 31. This forms an adjustable platform upon which the actuating cam plate 27 operates, which cam plate is adjusted with the pump plungers 14 by means of which all of the pump plungers are adjusted simultaneously and to the same extent with respect to the fixed inlet ports 12 in the pump cylinders. Such an adjustment of this carriage assembly effects an adjustment of the stroke of the pump plungers with respect to these fuel inlet ports to vary the amount of the discharge through the respective outlet ports of the pump cylinders.

In operation, fuel is supplied through a suitable connection designated generally at 7, to the fuel inlet chamber 6 in the top of the housing. The inlet ports 12 are controlled by the respective plungers 14, and when uncovered, as shown at the left in Fig. 2, fuel is admitted from chamber 6 to the pump chamber 11 on the down stroke of the plunger. The pump plungers 14 are reciprocated by the tappets 23 actuated by the cam 26 on the plate 27, against the tension of the return springs 16. The cam plate 27 is rotated by the drive shaft 37 connected with the engine or other source of power. Upon rotation of the cam plate 27, the cam 26 will press on the roller 25 of the tappet 23, moving the latter upward,

thus lifting the plunger 14 which is held in contact therewith by the spring 16. As the plunger is moved upward, a portion of the fluid in the pump chamber 11 is rejected or forced back through the inlet port 12 until the end of the plunger passes over and closes off the inlet port. From that point on the plunger displaces the fluid from the cylinder in its upward movement, past the check-valve 13a to the injection line leading to the engine cylinder or other point of injection.

It will be evident that the quantity of fuel that is injected upon each plunger stroke will depend upon the distance of travel of the plunger above the inlet port during the working stroke of the plunger. Although the plunger travels through the same distance on each stroke, its initial position relative to the inlet port will determine the length of its travel past the inlet port upon its upward movement in the pump chamber, and thus an adjustment of the pump plunger relative to the cylinder will vary the length of its travel past the intake port, thereby varying the quantity of fluid injected from the cylinder. In one extreme position of adjustment, the upper edge of the pump plunger would not completely close off the inlet port upon reaching its upper limit of travel, and there would be no injection of the fluid from the pump chamber, while the opposite limit of adjustment would provide for travel of the plunger from a point just below the inlet port to a point above the port for maximum amount of injection.

The slightly spiral splined connection 39 between the drive shaft 27 and the cam sleeve 28 provides for a slight circumferential adjustment of the cam plate during vertical adjustment of the carriage assembly. Thus when the assembly is adjusted upward for an increased amount of injection, the cam plate 26 is adjusted forward slightly, so that the lobe of the cam 26 passes under the tappet roller 25, earlier in the cycle, thereby providing automatically for an adjustment of the timing simultaneously with and in proportion to the adjustment of the quantity of injection.

The carriage assembly is so constructed as to permit of ready assembly and disassembly of the parts of the pump, as well as the adjustment described. The shelf plate 17 is of skeleton shape, or perforated, to receive readily therein the projecting end portions of the pump cylinders 8. In assembling this mechanism, the plungers 14 and their return springs 16 may be assembled in proper positions relative to the cylinders 8, and when the two housing sections are joined together, the shelf plate 17 can be anchored then to the adjustable carriage assembly by inserting the stud bolt 20 through the opening in the thimble 21 and securing it in place. The parts will then be ready for operation.

Although I have shown the cam structure for adjustment of the carriage assembly as formed somewhat resembling a coarse screw-thread, it will be evident that various modifications of this adjusting means may be made within this invention, which will accommodate the adjustment of the parts as described, by raising and lowering the carriage assembly relative to the housing.

Although the invention is described primarily as a fuel injection pump, it is evident that it may be used wherever desired to obtain a variable discharge of liquid under pump pressure, and is not limited to the pumping of fuel for internal combustion engines. The number of pump cylin-

ders provided should correspond with the number of cylinders or other devices to which the liquid is to be supplied under pressure, although the outlets from the several pump cylinders can be connected together as a common outlet, if desired, in which event the cam structure could be simplified since there would be no necessity for maintaining a timed relation of the outlet charges.

10 I claim:

1. In a liquid injection pump, the combination of a housing, a cylinder mounted in said housing and having intake and discharge openings, a plunger operatively mounted in the cylinder and having an edge in position to control the intake opening to trap a quantity of liquid in the cylinder and to discharge the same therefrom, a cam having operative bearing relation with the plunger, resilient means acting on the plunger in opposition to the cam, a bearing block supporting said cam and having means for journaling the same in the housing, means for operating said cam, means for adjusting the bearing block relative to the housing to vary the operating position 15 of the plunger relative to the cylinder, and means for adjusting the resilient means bodily upon adjustment of the bearing block to maintain uniform tension thereof on the plunger in different adjusted positions of the cam.

30 2. In a liquid injection pump, the combination of a housing, a cylinder mounted in said housing and having intake and discharge openings, a plunger operatively mounted in the cylinder and having an edge in position to control the 35 intake opening to trap a quantity of liquid in the cylinder and to discharge the same therefrom, a cam having operative bearing relation with the plunger, resilient means acting on the plunger in opposition to the cam, a bearing block supporting said cam within the housing and having means journaling the cam for operative movement, a drive shaft connecting with the cam, cam means connected with the bearing block for adjusting said bearing block relative to the housing to vary the operating position of the plunger 40 relative to the cylinder, and means for adjusting the resilient means bodily upon adjustment of the bearing block to maintain uniform tension thereof on the plunger in different adjusted positions of the cam.

45 3. In a liquid injection pump, the combination of a housing, a cylinder mounted in said housing and having intake and discharge openings, a plunger operatively mounted in the cylinder and having an edge in position to control the intake opening to trap a quantity of liquid in the cylinder and to discharge the same therefrom, a cam plate having cam means thereon in operative bearing relation with the plunger, a bearing block 50 supporting said cam in the housing and journaling said block for turning movement therein, a drive shaft having a slidably splined connection with the cam plate, resilient means bearing against the plunger in a direction opposite to the direction of the cam, means fixed to the bearing block for confining said resilient means, and means for adjusting said bearing block bodily 55 relative to the housing to vary the operating position of the plunger relative to the cylinder, said confining means being adjustable with the bearing block to maintain uniform tension on the plunger in different adjusted positions of the cam means.

60 4. In a fuel injection pump, the combination of a housing having a plurality of cylinders there-

in, each of said cylinders having intake and discharge openings, a plunger operatively mounted in each cylinder and having means to trap a quantity of fuel in the cylinder and to discharge the same therefrom, a bearing block mounted in the housing for slideable movement relative thereto, a cam carried by the bearing block in position for operating the respective plungers, adjusting means connected with said bearing block, resilient means bearing against each plunger in opposition to the cam, and means fixed to the bearing block for confining said resilient means.

5. In a liquid injection pump, the combination of a cylinder having intake and discharge openings, a plunger operatively mounted in the cylinder and having an edge in position to control the intake opening, means for operating said plunger to trap a quantity of liquid in the cylinder and to discharge the same therefrom, means bearing on said plunger and operating said plunger relative to the cylinder, means for bodily adjusting said operating means relative to the cylinder to vary the operating position of the piston with respect to the intake port in the cylinder, resilient means bearing against the plunger in opposition to the plunger operating means, and means fixed to the adjusting means for confining said resilient means.

6. In a fuel injection pump, the combination of a cylinder having intake and discharge openings, a plunger operatively mounted in said cylinder and constructed to trap a quantity of fuel in the cylinder and to discharge the same therefrom, operating means bearing against the plunger, resilient means bearing against the plunger in opposition to the operating means, and means for bodily adjusting the operating means and resilient means jointly to vary the position of the piston relative to the cylinder.

7. In a fuel injection pump, the combination of a cylinder having intake and discharge openings, a plunger operatively mounted in said cylinder and constructed to trap a quantity of fuel in the cylinder and to discharge the same therefrom, operating means bearing against the plunger, resilient means bearing against the plunger in opposition to the operating means, means for adjusting the operating means for varying the position of the plunger relative to the cylinder, and means for adjusting the position of the resilient means.

8. In a fuel injection pump, the combination of means forming a pump chamber having intake and discharge openings, a plunger operatively mounted in said pump chamber, means for operating said plunger, resilient means bearing against said plunger in opposition to the operating means, means confining said resilient means, and means for adjusting said confining means whereby the plunger is adjusted relative to the pump chamber.

9. In a liquid injection pump, the combination of a housing, a cylinder mounted in said housing and having intake and discharge openings, a plunger operatively mounted in the cylinder and having an edge in position to control the intake opening to trap a quantity of liquid in the cylinder and to discharge the same therefrom, a cam having operative bearing relation with the plunger, resilient means acting on the plunger in opposition to the cam, a bearing block having means for confining the resilient means, and means for adjusting the position of the bearing block and said confining means therewith relative to the cylinder.

ERNEST C. GAMBRELL.
